Primary Examiner — Kathleen L Jones(74) *Attorney, Agent, or Firm* — Getech Law LLC; Jun Ye(57) **CLAIM**

The ornamental design for a server panel, as shown and described.

DESCRIPTION

FIG. 1 is a top view of the server panel in accordance with the present design;

FIG. 2 is a bottom view thereof;

FIG. 3 is a front view thereof;

FIG. 4 is a back side view thereof;

FIG. 5 is a left side view thereof;

FIG. 6 is a right view thereof;

FIG. 7 is a perspective view thereof; and,

FIG. 8 is another perspective view thereof.

The features shown in broken lines in the various Figures are for illustrating environmental structure and form no part of the claimed design.

The interior features partially visible through the small elongated vent openings in FIGS. 1-3 and 8, which are too small to clearly depict in broken lines, form no part of the claimed design.

1 Claim, 8 Drawing Sheets(56)
